UNITED STATES PATENT OFFICE.

ALPHEE J. GALLANT, OF PORTLAND, MAINE.

DOOR-OPERATING MECHANISM.

Application filed February 11, 1922. Serial No. 535,880.

To all whom it may concern:

Be it known that I, ALPHEE J. GALLANT, a citizen of the United States, residing at Portland, in the county of Cumberland and 5 State of Maine, have invented new and useful Improvements in Door-Operating Mechanism, of which the following is a specification.

My invention relates to a mechanism for 10 opening and closing the line on an electric lighting circuit automatically, by the opening and closing of a door.

I am aware that there has, heretofore, been devices placed on the market which 15 attain this object, but in all cases, so far as I am aware, these devices have broken in directly on the main feed lines, necessitating "live" wiring to the door itself. This not only adds a fire hazard, but it is quite expensive to install, particularly if the apparatus is to be put in place after completion 20 of all wood and plaster work.

My mechanism may be set up in a very short time,—is therefore inexpensive to install; it is adapted to be used in conjunction 25 with any present-day socket using the chain pull principle for operating same, and can be quickly disengaged from the lighting fixture when it may be desirable to 30 use the latter independently.

By referring to the drawing accompanying these specifications the design of the apparatus can be clearly seen.

Fig. 1 is a plan showing door in closed position (full lines) and swung partly open (dot and dash lines); Fig. 2 is a side view, showing door swung open part way, and bell-crank and connecting wire in one of the extreme positions; Fig. 3 is a view of 40 the mechanism in perspective; Fig. 4 a sectional view through bell-crank and bracket on line $y-y$, Fig. 2; Fig. 5 is an enlarged view of adjustable door contact; Fig. 6 an assembly of mechanism showing how adjustability is obtained; and Fig. 7 a view 45 showing door closing and contact pin sliding under pawl. Similar numerals refer to similar parts in all the several views.

In Fig. 2, 1 is a wall, 3 represents a door, 50 shown closed, and within door casing 4. Mounted on wall 1 is a bracket 5, bifurcated at 6. On outer end of 6 is pivot pin 7, supported on which and held between the bifurcated arms 6 is bell-crank lever 8.

On the lower or vertical arm of 8 is pivoted 55 a pawl 9, a projecting part 10, on the

upper end of which holds pawl in alignment with arm 8 when pressure is applied to face of pawl at L, and in conjunction with spring 11 keeps pawl normally in this position except when pressure is applied in an opposite direction, as will be hereinafter referred to.

Secured to side of door, near the top, is a block 12, in a hole 13, drilled in the top 60 of which is a slidable member or contact pin 14. This pin is held securely in hole 13 by means of set screw 15, but is subject to adjustment vertically. Through a hole 16 in upper or horizontal arm of 8 is secured 65 a wire or cord 17, which extends upward and over a guide pulley, and so on to a chain pull.

In Fig. 4 is seen my method of connecting 70 up the bell-crank 8. Pin 7 is a drive fit in 8, and is also for emergency keyed to same by pin 20. A running fit for 7 is provided in arms 6—6 and extending outward from these arms on one side is mounted on pin 7 a spiral spring 21, one end of which 75 being secured to pin 7 and the other end to arm 6, keeps stop 22 on bell-crank lever 8, normally in close contact with under side of arm 6, which establishes the extreme left hand movement (as seen on drawing) of 80 bell-crank lever 8.

In operation, the door 3, opening, will bring contact pin 14 up to pawl 9, striking face L of same, and the door continuing 90 to open further will shortly be in a position as shown in Fig. 2, where pawl 9 is about to drop off from top of contact pin 14. As the door continues to open the pawl 9 will drop off contact pin 14 and assume 95 original position; thus the chain pull completes two cycles of movement,—out and in, this style of socket being of the type which is provided with a recoiling device which automatically pulls the chain back within 100 itself after release of the force which pulled it out.

At this stage the light is on and the door open. Closing the door will not affect position of parts, except as seen at Fig. 9, when on the return movement of contact pin 14 105 it strikes the pawl 9 on side marked R, simply lifting it and passing by to closed position of door.

The next time the door is opened the process is repeated, only, the opening of door 110 will turn off the light, already on. In other words,—two movements of door, open

and close, will turn on the light; then two more movements of door, open and close, will turn the light off.

In providing means for different lengths 5 of pull on chain I will refer to Fig. 5 in which it will be seen that by loosening set screw 15, contact pin 14 may be raised or lowered. Now by reference to Fig. 6 it will be observed that top of contact pin 14 trav- 10 els in a horizontal line 23-23, while lower end of pawl 9 moves on arc 24-24, the separating point being at intersection of these lines, or 25.

By raising pin 14 it will be seen that 15 pawl remains longer in contact with pin,— thus increasing stroke of bell-crank, and pull on chain on socket; and by lowering the pin 14 in the block 12 the reverse takes place,—or a shorter stroke.

20 My mechanism is designed so as to operate the socket switches independently of the automatic feature, and for this purpose I provide a hook on end of wire or rope 17, which can be readily detached from chain 25 on socket and the latter operated by means of drop cord with handle attached.

Having thus described my invention, I claim:

20 In a door operating mechanism, of the class described, the combination, with a door

swingingly mounted in a door-casing; of a member rigidly secured to and mounted near the top of said door, a hole drilled in the top of said member, a pin seated in said hole, means for rigidly holding said pin in 35 said hole in different vertical positions within said hole, a bifurcated bracket secured to the door casing adjacent the top of said door, and centrally positioned over and in alignment with said member on said door when 40 the latter is in closed position within said door casing, a bell crank lever pivoted within the bifurcations of said bracket, means for securing a cable or wire rod to the end of one of the arms of the said bell-crank 45 lever, a projecting stop on the inner edge of said arm to bear on said bifurcated bracket and restrict the movement, in one direction, of said arm, a spring operating to yieldingly hold said stop against said 50 bracket, a pawl pivotally hung to the end of the other arm of the said bell-crank lever, a spring adapted to hold the heel of said pawl yieldingly against the arm of said bell-crank lever and restrain the move- 55 ment of said pawl, around its axis, in one direction and allow of certain movement in the opposite direction, substantially as de- scribed.

ALPHEE J. GALLANT.
